CREAM COOLER

Max M. Guggenheim, New York, N. Y., assignor
to National Equipment Corporation, New York,
N. Y., a corporation of New York

Application September 16, 1948, Serial No. 49,540

4 Claims. (Cl. 107—7)

This invention relates to confectionery making machines, and particularly to those employed for cooling fondant or so-called "cream" employed in candy manufacture.

An object of the invention is to provide a machine of this character by which the fondant is rapidly cooled by a means which results in a product of superior texture and consistency. Another object of the invention is to provide a machine in which the cooling is rapidly and smoothly performed; in which the fondant is separated or divided into particles by suction exerted through a foraminous screen and then re-united into a cooled, superior product.

Still another object of the invention is to provide a machine which will continuously cause a flow of the fondant to be delivered to a cream beater, so that the movement of the cream from the cooking to the beating will be uninterrupted and production will be greatly increased.

These and other objects are attained by the invention, a more particular description of which will hereinafter appear and be set forth in the claims appended hereto.

In the accompanying drawing, wherein several illustrative embodiments of the invention are disclosed, Fig. 1 is a side elevation of a machine constructed in accordance with the invention; Fig. 2 is a top plan view of one of the kettles; Fig. 3 is a vertical sectional view through the vacuum dome, the upper portion of one of the kettles positioned below the same, and through surrounding parts of the structure; Fig. 4 is a vertical sectional view through the outlet head; Fig. 5 is a side elevation of a modified structure of the continuous type, and Fig. 6 is a view of the structure of Fig. 5 at right angles thereto.

With reference to the construction disclosed in Figs. 1 to 4 inclusive, 1, 2 and 3 indicates three of the vertical supporting posts or standards which arise from the floor and constitute part of the frame of the machine. Four of these posts are employed. Secured to the upper ends of these posts by the screws or bolts 4 is the top plate 40 which is provided with a central opening in which is mounted the lower open end of a vacuum dome 5. The upper end of the dome 5 is flanged, as indicated at 6, said flange being attached to the flange 7 at the end of a pipe or conduit 8 which extends to a vacuum pump or other suitable means for creating a vacuum and thus exerting "suction" within the dome 5 for a purpose to be hereinafter mentioned.

Leading into the interior of the dome 5 is the delivery or feed pipe 9 which extends through

the side wall of the dome. Within the dome is provided a continuation of said pipe consisting of a downwardly directed portion 10 carrying the outlet head 11 at its end. The outlet head 11 consists of a cup-shaped body 12 formed with a nipple 13 into which is received the end of the part 10 of the feed or delivery pipe 9. At its lower end, the delivery head is provided with a screen 14 which, as seen in Fig. 4, is provided with a plurality of small outlet holes 15 so that the screen is in fact, of a foraminous nature. The screen is of considerably larger diameter than pipe 10 and actually constitutes a spray head. The screen 14 is held in place in the head 11 by a clamping ring 16 attached to the circumferential flange 18 of the head 12 by means of the screws 17. While the outlet head is of substantially circular form, its shape and construction may be varied, the important feature of its construction residing in the employment of a multi-apertured screen through which the fondant is drawn by suction in a manner to be described.

At 19 is shown a suction control valve, provided with operating handle 20 by means of which the valve can be adjusted to cause it to open to permit the flow of fondant through it and through the pipe extension 10 and then through the delivery head 11, when the desired degree of vacuum is obtained within the dome 5. An observation window shown at 21 is provided in the dome 5.

Supported on brackets 22 on the supporting posts of the machine frame is a pair of horizontal rails, indicated respectively at 23 and 24. Said rails extend well beyond the posts of the frame and are of such a length as to enable two kettles, indicated respectively at 25 and 26 to be supported upon them. Thus while one kettle, or that indicated at 26 in Fig. 1, is being filled with fondant, the other kettle, or that shown in 25, is being emptied. Each kettle is provided at the top with a radially extending flange 27 secured to a substantially square frame 28 which has a downwardly extending side wall or flange 29 provided with flanged rollers 30 that ride upon the tops of the rails 23 and 24, as clearly seen in Fig. 1. These rollers permit the kettles to be rolled back and forth along the rails 23 and 24, and each of the frames 28 is provided with a handle 31 to facilitate manual movement of the kettle along the rails, as the operation of the machine requires it. Stops 32 are provided at the opposite ends of the rails to limit movement of the kettles. At the bottom of each kettle is provided a trap door 31a that is pivotally moved

to either open or closed position by means of the projecting handle 32. The cooled fondant is delivered through said trap door into a suitable receptacle.

When a kettle is positioned beneath the dome 5 and it is desired to fill the kettle with the fondant drawn by suction through the outlet head 11, it is necessary that a seal is obtained between the top of the kettle as positioned, and the lower end of the dome. How such a seal is obtained will be noted in Fig. 3. It will be therein noted that the top plate 40 is provided with a groove in its under face in which is mounted a sealing gasket 33 which continuously surrounds the lower open end of the dome 5. The top of the kettle located below the lower open end of the dome 5 seats against this gasket and thus an airtight seal is established between the dome and kettle. To effect this seal it is necessary that the kettle be raised to bring its top flange 27 into contact with the gasket 33, and for this purpose hydraulic cylinders 34 and 35 of known construction, are mounted on the inner sides of the rails 23 and 24 as clearly seen in Fig. 3.

At the proper time, and when the kettle is positioned below the dome 5, the hydraulic fluid is permitted to enter cylinders 34 and 35 causing the pistons therein to raise and bring their heads 36 into contact with the inserts or blocks 37 on the under side of the frame 28 to thus elevate the frame 28 and the kettle carried thereby and bring the flange 27 of the kettle into a firm sealing contact with the gasket 33, and hold the same in such contact during the operation of filling the kettle. When this is occurring it will be noted from Fig. 3 that the rollers 30 are slightly raised from the rails 23 and 24. After the kettle is filled, the hydraulic pressure in the cylinders 34 and 35 is reduced to allow the kettle to lower and its rollers to be brought to rest upon the rails 23 and 24. The kettle can then be rolled along the rails 23 and 24 to the position shown at 25 in Fig. 1, while an empty kettle is moved into the position below the dome 5 to be filled.

From the foregoing, the operation of the device will be readily understood. In Fig. 1 the kettle shown at 26 is in readiness to be filled since the same is positioned below the dome 5. Hydraulic pressure is then exerted in the cylinders 34 and 35, resulting in the pistons 36 thereof elevating the kettle 26 in the manner previously described, to establish a seal between the kettle and the dome 5. The vacuum-creating means is then set in operation and when a vacuum of the required degree is obtained in dome 5, the valve 19 will open, permitting the fondant to be sucked in through pipe 9 and to pass through the valve 19 and then pass through pipe portion 10 and out through the apertures 15 in the outlet head. The fondant, in passing through the foraminous plate or disk 14 is broken down or divided into particles or "snow" which not only cause the hot fondant to be materially and almost instantly cooled, but "fluffs" the material and as it falls down into the kettle 26 and collects therein it is not only greatly reduced in temperature but united into a mixture of syrupy and decidedly smooth texture. When a sufficient amount of the fondant is thus treated and the kettle 26 is filled, suction in the dome 5 can be released by operation of a release valve 41. By release of the hydraulic pressure in the cylinders 34 and 35, the kettle is lowered so that

its rollers 30 rest on the rails 23 and 24, and it may then be moved from below the dome 5, to the unoccupied portion on the rails 23 and 24, seen at the right in Fig. 1.

When the kettle 26 is moved from position below the dome 5, kettle 25 which has been emptied while kettle 26 was being filled, is then rolled to position it below the dome 5, and is raised to establish sealing contact with the dome. The filling procedure just described is then repeated. While this is taking place, the previously filled kettle is being emptied in readiness for its next refilling.

With the structure just described, kettles are successively used and require emptying as fast as they are filled. With the modified structure shown in Figs. 5 and 6, a continuous operation is provided by means of which the fondant may be uninterruptedly delivered into the dome and therefrom will be continuously delivered by a suitable pump means directly to cream beaters or to any other remote devices for treatment on the product after it has been cooled. In this embodiment of the invention the dome 5, while slightly different shape, is similar in function to that previously described. At the lower end of the dome is secured a conical receptacle 49 which is preferably fixedly but removably attached to the lower end of the dome, and has its smaller or outlet end 42 attached to the inlet of a pump 43. Said pump may be of known construction and of the type employed for the non-contaminating positive and continuous movement of fluids or semi-fluids. In the drawing, a helical gear type of pump is disclosed, the rotor thereof being indicated at 44 and being operated in a helical stator 45. A well-known type of pump in this construction is the "Moyno" and is satisfactory for the purpose described. The outlet of the pump 43 is shown at 46, and said outlet may be in communication with a cream beater or other apparatus to which it is desired to deliver the cooled cream for treatment or operation.

With the above-described device, the heated fondant is delivered into the dome 5 out of the foraminous delivery head 11 by suction exerted in the manner described in respect to the structure of Figs. 1 to 4 inclusive. The material discharged out of the delivery head, in particled or "snow" formation, will descend into the conical receptacle 49 beneath the dome 5 to unite and collect therein and to be drawn out by the pump 43 and delivered to the cream beater or to any other remote device or collection chamber as required. In first starting the apparatus, it may be found desirable to run the pump somewhat slowly so that the delivery of the fondant into the conical receptacle 49 will be faster than its removal therefrom by the pump 43. This will permit the material to accumulate in the receptacle 49 to a required height, such as for example, that indicated by the dotted line 50 in Fig. 5. Then the pump may be speeded up sufficiently to keep pace with the delivery of fondant into the receptacle 49 so that the product therein will thereafter maintain a constant height, namely, that indicated at 50, or other desired height, in the receptacle 41.

By means of devices herein described, the cooling of the heated fondant takes place rapidly and the dividing of the material by passing the same through a foraminous screen not only causes the rapid cooling as above pointed out,

but results in a mixture of greatly improved texture possessing lasting characteristics.

While I have herein described the material upon which the device operates as being a fondant or so-called "cream," it will be apparent that the device will not only effectively operate upon such specific material, but upon many other materials, among which may be included fudge, caramel, boiled sugar or any other kind of pasty materials.

In the structure of Fig. 5, the pipes shown at 52 and 53 are for the entry of steam and water into the dome 5 for the purpose of flushing out the dome after use. In this embodiment of the invention, the use of a pump is suggested for continuously removing the cooled material. Of course, other known means may be employed for this purpose.

While I have described several embodiments of the invention, it is obvious that the same is not to be restricted thereto, but is broad enough to cover all structures coming within the scope of the annexed claims.

What I claim is:

1. In a machine of the character described, a supporting frame, horizontal rails supported by said frame, a kettle movably supported on said rails, a chamber supported above the rails, said chamber having an open lower end, sealing means provided around the lower end of the chamber, means for elevating said kettle from the rails to bring the upper end of the kettle into contact with said sealing means and thereby close the lower end of the chamber and cause the kettle and chamber to cooperate in forming a vacuum chamber, a delivery pipe leading into the chamber above the kettle, said pipe having a foraminous outlet directed toward the kettle, whereby fondant will be suctionally drawn through said outlet by the vacuum exerted in the chamber and will fall down into the kettle.

2. In a machine of the character described, a supporting frame, a kettle movably supported thereon, a chamber above the frame, said chamber having an open lower end, sealing means at said open lower end, means for elevating the kettle to bring the top of the same into contact with said sealing means to cause the chamber

and kettle to cooperate to form a vacuum chamber, and means for suctionally conveying fondant into said vacuum chamber to cause the same to be deposited into the kettle.

3. In a machine of the character provided for in claim 2, wherein the elevating means for the kettle is hydraulically operated, and wherein the conveying means for the fondant includes a head located within the vacuum chamber having a multitude of small apertures through which the fondant is suctionally drawn to divide the same.

4. In a cream-cooling machine of the character described, a delivery conduit for hot cream or fondant, a head carried at the end of said conduit, said head having an outlet of foraminous nature, a hood surrounding the head and in which vacuum is developed to a degree sufficient to suctionally draw the fondant or cream through the foraminous outlet to thereby break up the fondant, a removable collection receptacle for receiving the fondant after the same has passed through the foraminous outlet, the hood having an open bottom beneath which the receptacle is adapted to be removably positioned, means for elevating the receptacle to bring its top into contact with the bottom of the hood and means for establishing a seal between the bottom of the hood and the top of the receptacle when the receptacle is so elevated so that when said receptacle is positioned below the hood and has been elevated into receiving position it will cooperate with the hood to form a vacuum chamber.

MAX M. GUGGENHEIM.
